(57) **CLAIM**

The ornamental design for the mobile phone protective housing, as shown and described.

DESCRIPTION

FIG. 1 is a perspective view of a mobile phone protective housing showing my new design;

FIG. 2 is a top plan view thereof;

FIG. 3 is a bottom plan view thereof;

FIG. 4 is a front elevational view thereof;

FIG. 5 is a rear elevational view thereof;

FIG. 6 is a right side elevational view thereof;

FIG. 7 is a left side elevational view thereof;

FIG. 8 is a reference drawing thereof in a usage state;

FIG. 9 is a perspective view of a second embodiment of a mobile phone protective housing showing my new design;

FIG. 10 is a top plan view thereof;

FIG. 11 is a bottom plan view thereof;

FIG. 12 is a front elevational view thereof;

FIG. 13 is a rear elevational view thereof;

FIG. 14 is a right side elevational view thereof;

FIG. 15 is a left side elevational view thereof;

FIG. 16 is a reference drawing thereof in a usage state;

FIG. 17 is a perspective view of a third embodiment of a mobile phone protective housing showing my new design;

FIG. 18 is a top plan view thereof;

FIG. 19 is a bottom plan view thereof;

FIG. 20 is a front elevational view thereof;

FIG. 21 is a rear elevational view thereof;

FIG. 22 is a right side elevational view thereof;

FIG. 23 is a left side elevational view thereof; and,

FIG. 24 is a reference drawing thereof in a usage state.

The broken lines showing on FIG. 8, FIG. 16 and FIG. 24 are for illustrative purposes only and form no part of the claimed design.
